SLEEVE ADJUSTER

Frank Walter, Altoona, Pa.

Application November 12, 1954, Serial No. 468,471

5 Claims. (Cl. 2—269)

The present invention relates to sleeve adjusters of 15 the character which are particularly useful for workmen.

A purpose of the invention is to provide a sleeve adjuster which can be manufactured and inserted in a shirt readily using machine methods.

A further purpose is to make a sleeve adjuster readily 20 adjustable from outside the shirt.

A further purpose is to provide a sleeve adjuster which is adapted to fit a wide variety of sleeve and arm sizes.

A further purpose is to minimize the tendency of the sleeve to hang down near the elbow when the arm is extended and thus reduce the likelihood that the sleeve will come in contact with machinery or work in process.

A further purpose is to more effectively ventilate the sleeve space when it is provided with a sleeve adjuster.

A further purpose is to make the sleeve adjuster more readily compensate for abnormal pull on different parts of the arm against the sleeve.

Further purposes appear in the specification and in the claims.

In the drawings I have chosen to illustrate one only of the numerous embodiments in which my invention may appear, selecting the form shown from the standpoints of convenience in illustration, satisfactory operation and clear demonstration of the principles involved.

Figure 1 is a fragmentary side elevation, partly in 40 axial section, showing the sleeve adjuster of the invention in position to allow the sleeve to extend fully down to the wrist.

Figure 2 is a view similar to Figure 1 showing the sleeve adjuster tending to hold the cuff above the wrist.

Figure 3 is an enlarged section on the line 3—3 of Figure 1.

Figure 4 is an enlarged fragmentary axial section through the sleeve and sleeve adjusting collar.

Efforts have been made in the past to provide sleeve 50 adjusters which will permit a wearer to adjust the cuff position to meet various requirements. Thus at one time it may be desired to have the sleeve extend fully down to the wrists, while at other times, to prevent soiling the cuffs and to prevent interference in work, it may be desired to pull the sleeve partially up so that the wrist is free.

Many of the devices of this kind have been difficult to produce with ordinary sewing machines and similar equipment, and therefore have been very expensive to make.

Difficulties have also been encountered with some of the sleeve adjusters because they were uncomfortable to wear, held the sleeve in an abnormal position, and were objectionable from an appearance standpoint because the sleeve adjuster showed through the sleeve.

Other difficulties have been encountered because the sleeve adjusters have been very hot to wear. There has furthermore been a problem in making the adjustment, as in some cases it has been necessary to reach into the interior of the sleeve, or to apply difficult manipula-

2

tion from outside the sleeve, thus running the danger of soiling the sleeve or causing abnormal wear.

Further difficulty has been caused in laundering because some sleeve adjusters have used metallic parts which are likely to tear or otherwise injure the shirt in passing through ironing equipment.

The device of the invention is a simplified and improved sleeve adjuster which is free from the above difficulties. The adjuster of the invention can be made 10 very simply and installed using ordinary sewing machines or hand sewing, and it can be used with a minimum of difficulty. The sleeve is adjustable from outside without complexity and hangs in a comfortable normal manner after adjustment.

The adjuster does not tend to distort the sleeve into an unusual position. The adjuster also has the great advantage that it prevents the sleeve from hanging down a considerable distance below the elbow and thus possibly coming into contact with machinery or work in process.

The invention is not inconvenient in laundering as the sleeve adjuster can be laundered with the shirt in the usual way.

Considering now the form shown in the drawings, the 25 shirt is provided with a sleeve 20 having a cuff 21.

On the inside of the sleeve adjacent and suitably extending above the elbow, cords 22 are secured in a longitudinally extending direction with respect to the sleeve by fastening as by sewing to the sleeve at the top at 30 23 and at the bottom at 24. The cords are distributed in spaced relation around the interior of the sleeve, desirably 3, 4 or more being provided at equally spaced positions.

Each of the cords forms a loop 25 which extends slightly 35 away from the inside of the sleeve and the cord passes through a gripper 26 which is located at a position corresponding to the cord around the outer edge of a sleeve adjusting collar 27. The gripper is desirably a rubber synthetic rubber tube which is slightly larger than the cord and allows space for an elongated stitch 28 of thread or the like to pass through the interior of the tube and be gathered at the side and sewed at 30 to the collar. The tube 26 desirably passes through a hole 31 in the collar.

The collar is made of fabric, and preferably a fabric having a high degree of elasticity. The preferred fabric is picot cloth, which is provided with picot eyelets 32 woven in making the cloth and allowing free ventilation in the sleeve space from above and below. The picot cloth is very elastic so that if abnormal forces are applied to one side of the sleeve the sleeve adjusting collar will by its elasticity make considerable allowance.

The sleeve adjusting collar may be made from a strip 55 sewed together at the end at 33 to form a ring. At the inside which is to engage the arm there is a drawstring hem 34 through which is threaded a drawstring 35 suitable of elastic drawstring material such as cotton, nylon or rubber. The drawstring passes out through open ends 36 in the hem, and is then at the two ends 60 threaded through a succession of gripping eyelets 37, 38 and 40 and 41, terminating in suitable buttons or tabs 42 at the opposite ends of the drawstring. It will be evident that one end of the drawstring can be fastened to the collar if desired.

The device may be applied to the shirt at the time of manufacture, or may subsequently be installed in the shirt by simply stitching the cords in the shirt at 23 and 24, which are the only points of attachment to the shirt.

In using the device, the wearer first adjusts the drawstring to fit the arm. It will normally be adjusted so that it will not be passed over the large portion of the

elbow but will remain comfortably on the arm above the elbow. When the shirt is to extend down toward the cuff the sleeve is simply pulled down and the collar rides up on the cords 22. When on the other hand it is desired to pull up the sleeve, it is merely necessary to move the cords 22 relatively upwardly in the grippers 26, so that the collar tends to hold the sleeve from moving down. When the sleeve is next to be pulled down this can be accomplished by merely pulling on the cuff or by pulling the cords through the collar by grasping the ends through the shirt.

Normally the drawstring merely has to be adjusted once and will be left in the adjusted position, where it is elastic.

When it is desired to launder the shirt, the adjuster is simply left in its normal position and it will go through washing and ironing without difficulty. The softness of the picot cloth aids in this respect. The softness of the picot cloth also aids in respect to resilient adjustment during wearing of the shirt.

When the wearer extends his arm, whether the sleeve adjuster is in one position or another, the sleeve adjuster tends to prevent the shirt from dropping excessively away from the elbow and against interference with equipment.

Free ventilation is permitted through the openings in the picot cloth and the picot cloth itself tends to absorb perspiration.

In view of my invention and disclosure variations and modifications to meet individual whim or particular need will doubtless become evident to others skilled in the art, to obtain all or part of the benefits of my invention without copying the apparatus shown, and I, therefore,

claim all such insofar as they fall within the reasonable spirit and scope of my claims.

Having thus described my invention what I claim as new and desire to secure by Letters Patent is:

- 5 1. In a sleeve adjuster for use on a sleeve, a plurality of cords extending longitudinally along the inside of the sleeve in spaced relation around the inside interior, a sleeve adjusting collar having an interior surface adapted to grip the arm, and extending outwardly from the interior surface to a position adjoining the sleeve around the circumference of the collar, and grippers on the collar through which the cords extend, frictionally engaging and holding the cords in any one of a selection of adjusted positions.
- 10 2. A sleeve adjuster according to claim 1, in combination with drawstring means around the interior of the collar adapted to adjust the arm engaging surface at the interior of the collar.
- 15 3. A sleeve adjuster according to claim 1, in which the collar is composed of picot cloth.
- 20 4. A sleeve adjuster according to claim 1, in which the grippers comprise elastomer tubing.
- 25 5. A sleeve adjuster according to claim 4, in which the grippers are held to the collar by stitches extending through the elastomer tubing and around the outside.
